Primary Examiner — Jae Liang*Assistant Examiner* — Tia Ruth-Renee Polidori**CLAIM**

The ornamental design for a water bottle, as shown and described.

DESCRIPTION

FIG. 1 is a front, top perspective view of a water bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Portions of the water bottle shown in evenly spaced broken line form no part of the claimed design.

The dot-dash broken line in FIG. 7 depicts the bounds of the claim and forms no part thereof.
